UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,397,967.

Specification of Letters Patent. Patented Nov. 22, 1921.

Application filed October 8, 1919. Serial No. 329,339.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler No. 436,532, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through distributing mechanism to the magazine from which they started.

15 In these machines as ordinarily constructed, the size of the matrices is considerably limited, and it is seldom attempted to employ therein matrix fonts above 18 pt. There has long been a demand in the trade

20 for machines capable of handling matrices of larger size, and many efforts have been made to meet such a demand. Thus, a special machine has been designed to permit the use therein of matrices assembled or set

25 up by hand in a stick or holder which may be inserted manually in the machine, it being possible in that way to employ matrices of the desired size. These special machines, however, have failed to meet the demands

30 of the trade because they lack the numerous advantages of the regular automatic linotypes, so that other efforts have been made to adapt these latter machines to the new conditions. Thus, it has been proposed

35 to divide an individual matrix font among two regular magazines, devoting each entirely to one-half thereof, but this arrangement is objectionable for obvious reasons, necessitating the use of two distinct distributors,

40 and leading into other complications. It has also been proposed to split the individual matrices of a font in halves and to run the complementary sections of such matrices in the same magazine channels in order that

45 characters of the required width may be used, but this arrangement is likewise unsatisfactory. Various other schemes have been suggested, but it would unduly prolong this specification to discuss them here. Suffice it to say, that of all prior arrangements, 60 none has completely solved the difficulty.

In my companion application Ser. No. 329,338, there is presented an automatic machine of the regular type which has been found in actual practice to answer completely the various requirements of the trade. This improved machine is not only capable of handling 18 pt. matrices, but matrices of a much larger size, up to 30 pt. wide, and this without changing the normal size or dimensions of the other machine elements, which it is desirable and important to preserve. That is to say, in my improved machine, the various parts have not been widened or extended (as might be done and as would naturally occur to one) in order to make use of matrices of the increased size, but they have been so modified otherwise that they will be adapted to handle the larger matrices. The various improvements by which these results are attained are fully pointed out in said companion application, to which reference may be had for full details.

My present invention is directed more particularly to a machine of the class just referred to and contemplates certain improvements designed to increase the capacity of such machine still further, as will be fully set forth in the detailed description to follow.

I have herein shown my invention merely in preferred form and by way of example, and obviously many changes and variations may be made therein without departing from its spirit. I therefore desire it to be understood that I do not limit myself to any specific form or embodiment except in so far as such limitations are specified in the claims.

100 Referring to the drawings:

Figure 1 is a front elevation of a portion of a linotype machine having my invention embodied therein;

105 Fig. 2 is a side elevation thereof, with the keyboard removed, and some of the parts shown in section;

110 Fig. 3 is an enlarged front view of a portion of the magazine-entrance and distributor bar, with the top plate of the entrance

removed, and showing several matrices in different stages of distribution.

Fig. 4 is an enlarged view of a detail;

Fig. 5 is a plan view, (partly diagrammatic) of the magazine, magazine-entrance and distributor bar, certain of the parts being broken away to show the form and arrangement of the interior parts;

Fig. 6 is a side elevation of the upper portion of the machine, showing in particular the arrangement and operation of the two interchangeable magazine-entrances;

Fig. 7 is an end view at one side of two of the proved magazines containing different matrix fonts, and showing by comparison the difference in sizes of the matrices of such fonts;

Fig. 7^a is a similar view showing the improved magazine in comparison with the regular linotype magazine and illustrating the difference in the sizes of the matrices capable of being stored therein;

Fig. 8 is a rear view at opposite sides of the parts shown in Fig. 6;

Fig. 9 is a view similar to Fig. 5, taken in connection with a substitute magazine-entrance, and showing in particular the different arrangement of its partitions and channels;

Fig. 9^a is a comparative view of two groups of detached matrices taken from different fonts;

Fig. 10 is a side elevation of the keyboard mechanism, the parts at the rear being shown in vertical section;

Fig. 11 is a section taken on the line 11—11 of Fig. 10;

Fig. 12 is a section taken on the line 12—12 of Fig. 10;

Fig. 13 is a perspective view of a detached portion of the keyboard devices, illustrating in particular the shiftable supporting frame wherein the actuating slides for the cam yokes are mounted;

Fig. 14 is a vertical section taken on the line 14—14 of Fig. 12;

Fig. 15 is a similar view showing the parts in different position;

Fig. 16 is a view similar to Fig. 12 showing on an enlarged scale certain of the parts detached;

Fig. 17 is a section taken on the line 17—17 of Fig. 16;

Fig. 18 is a similar view showing the parts in different position;

Fig. 19 is a diagram showing the new relation between the keyboard devices and the magazine wherein the matrices are stored.

The matrices X or Z are stored in the channelled magazine A and are released therefrom by the escapements E¹ (Fig. 2) under the influence of the keyboard E, whence they pass through the channelled front-plate or raceway B onto the inclined conveyer belt B¹, which delivers them to the

assembler B² wherein they are composed in line. After casting, the matrices are carried upward and transferred one at a time to the distributor bar C along which they are propelled by the conveying screws C¹ and which releases them at different points in its length according to character and drops them into a channelled magazine-entrance D or F for return to their proper channels in the magazine. The magazine A is supported upon the base frame A¹ which is arranged to be swung upwardly to disengage the magazine from the underlying bank of escapements E¹ (whose supporting bar A⁷ is mounted in the fixed machine frame) and locate it above the front-plate B, as shown by the dotted lines in Fig. 2, when it may be drawn forwardly from the front of the machine. To effect this swinging of the base frame A¹, it is pivotally mounted at its upper end upon the transverse rod A² and is provided at its lower end with the pair of cams A³ fast to the opposite ends of the transverse rock shaft A⁴ journaled in the base frame, the cams being arranged to co-operate with the rollers A⁵ on the machine frame and being operated by the arm A⁶ fast to the rock shaft A⁴, all as shown and described in detail in either of the patents to T. S. Homans, Nos. 814,542 and 829,969.

In the companion application before referred to, there are set forth certain improvements intended to provide for the use of matrix fonts up to say 30 pt. wide.

Generally speaking, such matrix fonts (herein designated X) comprise but seventy-two characters as distinguished from ninety characters of the ordinary fonts, the characters eliminated being those of the combined letter variety such as fi, fl, ffi, etc., and a few miscellaneous characters; and the space which would otherwise be taken up by these omitted characters in the different parts of the machine is utilized to enlarge the space devoted therein to the remaining characters of the font in such manner that the individual matrices may be increased in thickness in proportion to the additional space afforded by the reduced number of characters.

Referring first to the magazine A, it is of the regular trapezoidal shape and is provided on the inner faces of its top and bottom plates with series of ribs a' presenting sets of opposing grooves a (Fig. 5), which converge from the upper to the lower ends thereof and provide channels wherein the projecting ears X¹ of the matrices X engage. As shown, there are seventy-three such grooved channels a, two for the letter "e" and one for each remaining character of the new font, and these channels as so reduced in number are spaced apart throughout the entire width of the magazine. As illustrated in Fig. 5, the grooved channels

converge from unequally spaced points at the upper or receiving end of the magazine to unequally spaced points at its lower or discharge end, which points are determined 5 with reference to the varying set widths of the different characters of the largest matrix font, those at the lower end of the magazine being located to provide for the discharge of the matrices from the respective channels 10 without interference, and those at the upper end thereof being located to provide for the distribution of the matrices into said channels. It is pointed out, however, that in determining these points, the increased space 15 afforded by the reduced number of channels (namely, seventy-three) is divided or apportioned among them at both their lower and upper ends, not equally, but proportionately according to the varying set widths of the 20 different characters of the largest matrix font, so as in this way to take full advantage of the increased space.

Although differing radically in number and arrangement of its grooves *a* the magazine A is the same in size or width throughout as the standard or regular "Model 5" magazine now in general commercial use. The difference in the number and arrangement of the grooves is illustrated in Fig. 7^a, 25 which shows at the discharge end a portion of the improved magazine A in comparison with a similar portion of a "Model 5" magazine Y, which latter of course is formed with ninety-one sets (the standard number) 30 of grooves *y*, spaced apart in the usual manner. From this comparison, it will be seen that, due to the novel spacing of the grooves of the improved magazine, the size of the matrices X (lower case) stored therein is 35 considerably greater than that of the usual matrices W contained in the regular magazine, although both magazines are of the same width. This difference is even more pronounced with the upper case matrices. 40 The increased space thus provided in the magazine A amounts approximately to 25% and when apportioned among its channels as above described enables them to accommodate matrices of corresponding increased 45 size.

As the magazine A is of the same width at its receiving end as the standard or regular "Model 5" magazine, as above described, the magazine-entrance D may be and is of 50 the same width as the regular ninety-one channelled magazine-entrance which co-operates with such standard magazine, but the number and arrangement of the partitions *d* which divide it into matrix channels have 55 been changed so as to provide but seventy-three such channels, one for each channel of the magazine and of a width suitable for matrices passing therethrough. That is to say (Fig. 5), the partitions *d* when thus reduced in number are spaced apart through-

out the entire width of the entrance and are separated different distances from each other so as to apportion the full space of the entrance among the seventy-three intervening channels in accordance with the set widths 70 of the different characters of the largest matrix font, it being remembered that the magazine grooves *a* are unequally spaced apart at their upper ends to correspond with the varying widths and locations of the entrance channels. In the present instance, then, the increased space afforded by the reduced number of entrance channels is divided or apportioned among them proportionately according to the varying set widths 75 80 of the different characters of the largest matrix font.

Similarly, the distributor bar C is of the same length as the regular ninety-one combination bar employed in connection with 85 the "Model 5" magazine and magazine-entrance. However, to adapt it to its new conditions, the bar C is formed with only seventy-three combinations *c*, one for each channel of the magazine and magazine-entrance, 90 and these combinations are spaced apart throughout the entire length of the bar, and at unequal distances, so as to correspond with the location of the entrance channels. That is to say, the increased space afforded 95 by the reduced number of bar-combinations is divided or apportioned among them proportionately according to the varying set widths of the different characters of the 100 largest matrix font.

The entrance D is provided with supplemental guiding means to engage the matrices as they pass therethrough and direct them in proper position and under positive control into the proper channels of the magazine. Such means are presented in the Butts Patent No. 1,099,486 and are embodied herein in precisely the same form for most of the channels, consisting of guiding surfaces or bent over flanges *d*¹ projecting in 110 pairs into the entrance channels from the partitions *d* in position to engage the projecting ears X¹ on the opposite edges of the matrices X. Hence, and as more fully brought out in the Butts patent, the individual matrices, though of varying thicknesses in the different fonts, will be guided from the entrance channels in a straight or upright condition and caused to enter the magazine grooves in proper position. 115

However, there is a further difficulty arising from the use of extremely wide entrance channels which has had to be overcome. When the thin matrices are run through these wider channels, they are apt to topple 125 over so far that their projecting ears will not be engaged by the guiding flanges *d*¹. This condition is illustrated in Fig. 4, which shows by the full lines a thick matrix under control of the flanges and by the dotted lines 130

- a thin matrix which has passed beyond their control due to the abnormally inclined position which it can assume within the entrance channel (see also Fig. 3). Such a thin matrix, therefore, may jam and cause a piling up of the succeeding matrices. To overcome this difficulty, the guiding surfaces or flanges d^1 for such wide channels are located on relatively inclined leaf sections or tongues d^2 (Fig. 3) suitably joined at their upper ends to the partitions d about midway of the channels and having their lower ends turned back on themselves within the channels to form loops d^3 which act as spacers to separate the tongues from the partitions and hold the former at the required inclination. As a result of this arrangement, the affected channels are contracted in width in advance of the guiding flanges d^1 to such extent that while the larger matrices may pass freely therethrough, the thinner ones will be prevented from falling over so far as not to present their projecting ears to the guiding action of the flanges, this being brought about, of course, by the tongues d^2 which guide the matrices by their side faces until their projecting ears become engaged by the flanges. These tongues are further advantageous in that they permit the use of a single partition as the side-walls for adjoining entrance channels when otherwise extra partitions might be necessary, and in general they allow the channels to be made wider for any purpose. In addition, the tongues serve to contract the widths of the entrance channels without altering the positions of the partitions constituting the side-walls thereof, which feature is particularly useful when it is desired to change the width of one channel without affecting the width of the adjoining channel, as would necessarily result by the adjustment of the partition itself. The foregoing and various other improvements are described in great detail in the companion application Serial No. 329,338 above mentioned, and it would therefore be superfluous to discuss them further herein.
- As before explained, the present invention is directed more particularly to certain improvements in the class of machine above discussed. The improvements first to be described are intended to adapt the parts in their present form to handle matrices of the larger sizes, *i. e.*, above 30 pt., thus increasing the capacity of the machine to its fullest extent. In carrying out this feature, fonts of matrices Z comprising only fifty-five characters are employed, the additional space afforded by the elimination of the seventeen further characters (which are the figures and a few miscellaneous characters as indicated by the shaded key buttons in Fig. 19) being utilized to increase still further the size or thickness of the individual matrices. In this instance, the desired re-

sults are realized by altering the usual form of the matrices and by employing a further magazine-entrance F which may be substituted for the entrance D when desired.

In Fig. 9, a group of matrices Z is shown at the left and a similar group of matrices X at the right. As will be apparent, the latter matrices which are of usual form except of course as to size, have their projecting ears X^1 flush with the right side (which is the leading side during distribution and the following side during composition), and their tooth-combinations X^2 flush with the opposite or left side, these positions of the projecting ears and tooth-combinations being the same for all matrices of the font. On the other hand, the matrices Z which are of improved form, have their projecting ears Z^1 and tooth-combinations Z^2 located in different setwise positions on the respective matrices of the font, the location of the ears being different from and independent of that of the combinations, for reasons which will later appear. By thus varying the setwise positions of their projecting ears, the matrices Z of a given font may be stored in the magazine A so as to occupy the entire space accorded by its full width. Such a magazine with the contained font is shown in end view in the diagram of Fig. 19, wherein the different relative positions of the projecting ears on the respective matrices of the largest font above 30 pt. are clearly indicated. It will be observed that as so arranged, certain of the matrices Z occupy single channels as before and others two or more channels in whole or in part, the body portions of the matrices extending both to the left and right of the projecting ears Z^1 due to their different setwise positions thereon. In this way, the entire space of the magazine may be devoted to and apportioned among the fifty-five columns of matrices, which may consequently be increased in size or thickness in proportion to the space so gained, amounting approximately to 32% as compared with the seventy-two character fonts and to 57% as compared with the regular ninety-character fonts.

Fig. 7, for the sake of comparison, shows in end view portions of two magazines A, one containing the matrices X, and the other the matrices Z, and the difference in the size and arrangement of the matrices of the two fonts is apparent. It may be noted at this point that the matrices Z are arranged in the magazine in a different order as to character from that of the matrices X; this condition being illustrated in the diagram of Fig. 19, wherein the characters at the top connected by leader lines to the magazine channels denote the character arrangement of the matrix fonts X, and the characters applied to the matrices Z contained

within the magazine indicate the character arrangement of these fonts. This different character arrangement of the matrices Z has been resorted to in order that they may be 5 stored to the best advantage in the grooved channels of the magazines A and discharged therefrom without interference.

Referring now to the special magazine-entrance F, which is employed in connection 10 with the matrix fonts Z, it (like the entrance D), is of normal width and is provided with partitions f spaced throughout its entire width and dividing it into matrix channels. In this instance, however, there are but fifty- 15 five channels, one for each character in an individual font (there being no double "e" channels) or for each matrix column in the magazine, and the widths of these channels vary relatively in accordance with the set 20 widths of the different characters of the largest matrix font. Now, as ordinarily, the partitions d of the entrance D (see Fig. 5), are located in vertical planes passing substantially through the releasing points of 25 the bar combinations c. While such an arrangement is suitable for matrices of usual form, such as the matrices X, (whose projecting ears X¹ are located in the same setwise positions on all of the matrices of an 30 individual font and whose body portions extend only to the left of such projecting ears, Fig. 7), it is entirely unsuitable for the matrices Z, which in some cases not only occupy more than one magazine channel but 35 whose body portions extend both to the left and right of their projecting ears Z¹, as before mentioned. Hence, to adapt the entrance F to the matrices Z of such different form, its partitions f are arranged in dif- 40 ferent positions with reference to the magazine ribs a¹ and the bar combinations c, some being located in and others out of registry with the magazine ribs, and some lying in vertical planes passing through the 45 releasing points of the bar-combinations, and others lying in vertical planes offset from such combinations at one distance or another. The effect of this arrangement is that the entrance channels occupy varying 50 relations, not only to the magazine grooves a, but also to the bar combinations c, these varying relations enabling the channels to communicate with the appropriate sets of magazine grooves and in such manner that 55 the matrices may be conducted through the channels with their projecting ears in position to enter the required set of grooves. The specific arrangement of the partitions f is best shown in Fig. 9, wherein the releas- 60 ing points of the corresponding bar combinations c are indicated by the dotted lines, and wherein the extent of the lateral displacement of the various partitions is clearly shown. It will be noted, however, 65 that many of the partitions (like the ordi-

nary partitions) register with the magazine ribs and are disposed in vertical planes passing through the releasing points of the bar combinations, which arrangement has been made wherever possible. It should also be 70 noted that some of the channels (marked f³) are not used, the two partitions between which each such channel occurs acting only as the left and right side walls respectively of the two adjacent active channels whose 75 relative locations are such that a single partition may not conveniently act as a common wall for both.

The foregoing arrangement of the entrance partitions is permitted and provided 80 for by varying the setwise positions of the tooth-combinations Z² on the matrices Z as before referred to. These different setwise positions of the tooth-combinations throughout the largest individual font above 30 pt. 85 are indicated in Fig. 9, which for the purpose shows all of the matrices of the font as in the process of distribution. For the sake of clearness, however, the tooth-combinations themselves are not shown, but their 90 different relative positions on the respective matrices are indicated by the longer dotted lines which are extended downwardly from the releasing points of the active bar-combinations c, the shorter dotted 95 lines indicating the releasing points of the inactive combinations or those not used for the matrices Z. It will be observed that in most instances the tooth-combinations are located at or flush with the rear sides of the 100 matrices as customary, the partitions having been arranged to permit this wherever possible, but in many instances, the tooth-combinations are located toward the center of the matrices or away from the rear sides 105 thereof so as to drop them into the corresponding entrance channels, whose left or rear side walls are displaced laterally from the releasing points of the respective bar-combinations. In the present arrangement 110 the tooth-combinations Z² are changed to correspond with the character arrangement of the matrices Z in the magazine and consequently differ from those of the matrices X as well as those of the ordinary ninety-character fonts, thus following the common practice of rearranging the matrix combinations. Since some of the bar-combinations, as above indicated, will not be used in the distribution 115 of the matrices Z, it will be understood 120 that the foregoing remarks concern only the remaining or active bar-combinations whose relation to the entrance channels determine the setwise positions of the tooth-combinations on the matrices Z. In view of the 125 above construction and arrangement of the parts, when a magazine containing a font of matrices Z is inserted in the machine, it is merely necessary to locate the entrance F in operative position, when the proper dis- 130

tribution of the matrices will be insured. In other words, by interchanging the magazine entrances D and F, the machine may be adapted to handle any desired font of matrices.

To effect this interchange of the entrances, they are movably mounted in such manner that either may be brought into operative relation to the distributor and the selected 10 magazine at will. The entrance D (Fig. 8) is pivoted by a stud D¹ to the magazine base frame A¹ so as to be swung downwardly to inoperative position or upwardly to operative position, a spring D² being employed to 15 hold it yieldingly in the latter position. The entrance F, on the other hand, is pivoted at opposite sides by studs F¹ to a pair of arms F² fast to a rock shaft F³ which is journaled in the lower ends of arms F⁴ pivotally suspended from a transverse rod F⁵ of the framework, the whole constituting a swinging frame which may be turned about the rod F⁵ as an axis to locate the entrance in operative position, as shown by the full 20 lines in Fig. 6 or in inoperative position as shown by the dotted lines in said figure. It is held in the latter position by a detent F¹⁰ located on the framework in position to engage in an opening F¹¹ in one of the arms 25 F⁴. When in its operative position, the entrance is locked to the magazine base frame A¹ by detents F⁹ passing through the pivot studs F¹ and engaging in recesses in the outer ends of the pivot studs D¹ of the entrance D (Fig. 8). The two pairs of arms F² and F⁴ (constituting respectively the lower and upper sections of the frame) are formed with stop shoulders F⁶ which in the 30 normal position of the parts are held in engagement by springs F⁷, one attached at its opposite ends to the two arms of one pair, and the other connecting the upper arm F⁴ of the second pair with a lug F⁸ projecting laterally from the entrance, said lug being 35 adapted to engage the lower arm F² of such second pair and thus to limit the pivotal movement of the entrance in one direction. By reason of this construction, the entrance F may be freely turned within its supporting 40 frame to and from operative position while said frame is locked to the magazine base frame. Similarly, the magazine base frame is free to be rocked upwardly to permit the removal of the magazine without unlocking 45 the entrance frame which at such time yields through the relative movement of the arms F² and F⁴ (see dotted lines in Fig. 6). The manipulation of the entrances will now be clear. When a magazine containing a font 50 of matrices X is inserted in the machine, the entrance D is swung to operative position and the entrance F to inoperative position, as in Fig. 2; whereas, when a magazine containing a font of matrices Z is substituted, 55 the entrance F is brought to operative po-

sition and the entrance D thrown down to inoperative position, as in Fig. 6.

As the matrices Z also vary in thickness according to font, it is desirable to provide the entrance F (like the entrance D) with supplemental means to guide the matrices into the appropriate magazine grooves. To this end (Fig. 9), the partitions f are provided at their lower ends with guiding surfaces or bent-over flanges f¹ which are arranged to engage the projecting ears Z¹ of the matrices and guide them positively into the correct set of magazine grooves a. As shown, some of the channels have but one set of guiding flanges, whereas others are provided with two sets of such flanges. When equipped with a double set of flanges, the channels are enabled to discharge the matrices therefrom in correct position independently of the partitions f, which therefore are not required to be flush with the straight side walls of the magazine grooves a, as would otherwise be necessary in handling the thinner matrices. Some of the partitions f are also formed with leaf sections or tongues f² (identical with the tongues d²) carrying the guiding flanges f¹ and which gradually diminish the widths of the appropriate channels to adapt them to take care of the thinner matrices passing therethrough, precisely as described in connection with the matrices X, although the advantages previously mentioned are even more pronounced in the case of these leaf sections or tongues f².

The manner in which the matrices are released from the magazines will now be described, reference being had to Figs. 10 to 19. It has already been pointed out that the matrices Z of the larger or fifty-five character fonts are arranged in the magazine in a different order as to character from that of the matrices X of the smaller or seventy-two character fonts, so that these fonts not only differ as to number of characters but also as to character arrangement of the matrices in the magazines. The present improvements provide means whereby the key-board E may be operatively connected to the magazine in use, whether it contains a font or matrices X or a font of matrices Z, and in such manner that the finger keys will effect the release of the matrices bearing the same character in either case, a feature which I believe to be broadly new. In the embodiment illustrated, the keyboard comprises but seventy-two keys, one for each character of the matrix font X, and the intermediate parts are reduced to correspond.

Referring now in detail to the construction of the parts (Fig. 2), the escapements E¹, one for each channel of the magazine, or seventy-three in all, are actuated in the usual way by the corresponding series of

reeds E² (Fig. 10), which in turn are operated by the yokes E³ arranged in banks and provided with the cams or eccentrics E⁴ adapted under the influence of the trip dogs 5 or triggers E⁵ to coöperate with the underlying-power driven rolls E⁶, the triggers E⁵ being controlled from the finger keys E in a manner presently to be described. This arrangement of the parts is illustrated dia- 10 grammatically in Fig. 19, and it will be noted that the finger keys and intermediate parts lie substantially in the vertical planes of the corresponding magazine channels, as usual.

15 The mechanism through which the finger keys E act in effecting the operation of the cam yokes comprises two series of slides E⁷, E⁸, and a series of U-shaped rocking bails E⁹ (Figs. 10 and 12). The slides E⁷, E⁸, 20 are disposed in pairs, one for each finger key and its respective trip dog E⁵, and are arranged to be shifted laterally so as to be alternately engaged with the corresponding finger keys. The bails E⁹ are located in rear 25 of the slides and are disposed in superposed groups, one for each bank of finger keys, the bails of each group having their parallel arms separated different distances and arranged to coöperate with different pairs of 30 slides in such manner that when the slides are shifted laterally, those of one series will be engaged with the corresponding finger keys and the contiguous arms of the associated bails, and those of the other 35 series engaged only with the other arms of the bails, and vice versa. To provide for such engagement of the parts, the slides E⁷, E⁸, are formed in their forward edges with notches e¹ wherein the finger keys engage, 40 and in their rear edges with notches e² wherein the arms of the bails engage, it being noted that the notches e² of the slides E⁷ are wider than those of the slides E⁸ for reasons which will presently appear (Figs. 45 16-18).

The slides E⁷ are employed to make up a series of direct connections between the finger keys E and the escapements E¹ in effecting the release of the matrices X from 50 the magazine, while the slides E⁸ through the medium of the bails E⁹ and other slides E⁷ are utilized to make up another series of indirect connections between the finger keys and the escapements in effecting the release 55 of the matrices Z. Accordingly, the slides E⁷ are extended sufficiently to make connection with the trip dogs E⁵, being formed at their upper ends with notches e wherein the dogs engage, which notches are of such lat- 60 eral extent as to maintain their engagement with the dogs in either position of the slides (Fig. 13). On the other hand, the slides E⁸ stop short of the trip dogs so as to be entirely free thereof. Hence, when the finger 65 keys E are engaged with the slides E⁷ (Figs.

12 and 17), the latter through their direct connection with the trip dogs E⁵ through the associated cam yokes E³ into action and cause the operation of the escapement actuating reeds E², the bails E⁹ at this time being 70 unaffected due to the presence of the widened notches e² of the slides E⁷. In this condition of the parts, the finger keys are connected directly to the magazine, and in the usual manner, each finger key and the 75 intermediate parts being located substantially in the same vertical plane as the corresponding magazine channel. When, however, the finger keys are engaged with the free slides E⁸ (Figs. 18 and 19), the latter 80 do not affect the overlying cam yokes but, through the medium of the bails E⁹, transmit the motion of the keys to the active slides E⁷ of other cam yokes, which are thus thrown into action to operate the escapement 85 reeds E² located thereabove, it being remembered that the active slides, though disengaged from their corresponding finger keys, still maintain their connection with the cam yokes. In this condition of the parts, the 90 finger keys are indirectly connected to the magazine so as to effect the release of the matrices in the required manner, the finger keys being located in planes offset at various 95 distances from the matrix columns with which they coöperate in accordance with the character arrangement of the matrices in the magazine.

By referring to the diagram of Fig. 19, it will be noted that except in the case of the comma, every one of the matrices Z occupies a different channel in the magazine from that of the matrix X bearing the same character. Since the location of the comma-matrices is unchanged, the same connections 100 from the finger key may be used for all fonts. In such case, therefore, and as no bail is required, the slides E⁷, E⁸ of the corresponding pair are directly attached or made integral, so that the finger key is 110 permanently connected to the associated cam yoke and throws it into action in either position of the slides. In the case of the remaining matrices, however, they will require the use of the bails E⁹, so that fifty-four of 115 such bails are provided, each being arranged to connect the associated finger key to that escapement serving the magazine channel wherein the matrices Z bearing the same character are stored. This condition of the 120 parts is illustrated in Fig. 19 (the key buttons of the unused keys being shaded), but for the sake of clearness only one group of bails is illustrated, namely, that for the third row or bank of finger keys, it being understood that these bails in their mechanical embodiment are all located at the rear of the slides at the same level and upon a common pivot (see Fig. 12). The connections from 125 any one of the keys may be easily traced: 130

Taking the letter "a," for instance, its finger key is engaged with the associated free slide E⁸, which is connected by the relatively short bail E⁹ to the active slide E⁷ associated with the "e" finger key, offset to the left thereof. Such active slide, though disengaged from its finger key, maintains its connection with the trip dog E⁵, which therefore, in response to the actuation of the "a" finger key, throws the connected cam yoke E³ into action to operate the actuating reed E² for the escapement E¹ of the magazine wherein matrices X bearing the letter "e" are stored and which is now occupied by matrices Z bearing the letter "a". Similarly, in the case of the letter "r," its finger key is engaged with a free slide E⁸ which is connected by the corresponding bail E⁹ (extending more than half way across the keyboard) to the active slide E⁷ associated with the "I" finger key, so that this active slide through the medium of the connected trip dog E⁵, cam yoke E³ and reed E², causes the actuation of the escapement E¹ acting in the magazine channel occupied by matrices X bearing the letter "I," and now containing matrices Z bearing the letter "r". The connections from the other keys may be traced in like manner, it being apparent that in each instance the bails serve to permit the finger keys to coöperate with matrix columns in the magazine offset from or located to one side of the corresponding finger keys.

The bails E⁹ thus indicated diagrammatically in Fig. 19 are shown in their mechanical embodiment in Fig. 12, but in the figure, the active slides E⁷ are in engagement with the finger keys so that the bails are idle. It can be seen, however, that when the slides are shifted to the left to engage the finger keys with the free slides E⁸, the bails will also become engaged with such slides and will connect them with the active slides of other pairs marked e i h z ? I P Z, respectively, to denote the finger keys with which they are associated, or with which they are engaged in the other position of the slides.

It will now be clear that by merely shifting the slides E⁷, E⁸, laterally in one direction or the other, the keyboard may be operatively connected to a magazine containing a font of matrices X or a magazine containing a font of matrices Z, notwithstanding the difference in the number and arrangement of the characters in these fonts. However, to make the operation entirely clear, reference may be had to Figs. 16 to 18 which show the parts in different stages of adjustment. In Figs. 16 and 17, an active slide E⁷ is shown as engaged with the "R" finger key which therefore, when actuated, will lift this slide to trip the connected cam yoke and operate the escapement lying in the same plane, as required in effecting the release of mat-

rices X bearing the same letter. At this time, the bail E⁹ is idle, being engaged at one end in the widened notch e² of the slide E⁷, and at its other end in the notch e² of the free slide E⁸, which of course is disengaged from its corresponding finger key. When, now, the slides are shifted to their other position, as shown in Fig. 18, the "R" finger key is disengaged from its active slide E⁷ and engaged with the companion free slide E⁸, which latter is connected by means of the bail E⁹ with the active slide E⁷ of the finger key for the hyphen, so that the actuation of the "R" finger key will result in the operation of the cam yoke of the other key, as required in effecting the release of matrices Z bearing the letter "R."

It will also be noted that, in the latter position of the parts, the finger key bearing the numeral 8 (representative of the keys not used for the matrix fonts Z) is also engaged with its free slide E⁸, but since no bail is associated with such slide, the finger key is disconnected from any one of the cam yokes and hence will have no effect upon the other parts if it should be accidentally actuated. As a matter of fact, at such time the finger key will be positively locked against action by means later to be described. However, when the parts are in the first position, this numeral finger key will be engaged with its other slide E⁷, which is actively connected to the associated cam yoke, so that its actuation at that time will effect the proper release of the corresponding matrices X of the other fonts.

It will be seen, therefore, that in effecting the release of the matrices X from the magazine, all the escapements are actuated by the keyboard, whereas in effecting the release of the matrices Z, some of the finger keys (seventeen of them), and hence as many different escapements, are rendered inactive, although the remaining keys are actively connected to the rest of the escapements, which are those serving the magazine channels wherein the corresponding matrices are stored. The finger keys and the escapement actuating reeds may therefore be regarded as divided into groups, one of which alone is adapted to be used in the release of matrices of one font (the matrices Z), and all of which are adapted to be used conjointly in the release of the matrices of another font (the matrices X), the means before described acting to permit or prevent the joint operation of said groups as required. In this connection, however, it will be remembered that the matrices X and Z are arranged in a different order as to character in the magazine, and that the operative connections between the keyboard and the magazine are such as to enable the finger keys when actuated to effect the release of matrices bearing the same character irrespective

of the font in use. As before described, the alteration of the key-board to adapt it to one font or another is brought about merely by shifting the slides E^7 , E^8 , in one direction or 5 the other.

To effect such shifting of the slides E^7 , E^8 , they are carried by a slidable supporting frame H provided at the top and bottom thereof with attached comb plates H^1 , where- 10 in the slides are mounted in the usual way (Figs. 10 and 13). The supporting frame is formed with leg portions H^4 resting upon brackets H^5 of the machine frame and further with slotted portions H^2 engaging with 15 headed pins or screws H^3 on the machine frame, this mounting being such that the supporting frame may be slid freely in opposite directions to the required extents, as limited by the engagement of the screws H^3 20 with the ends of the slots of the portions H^2 . In order that the frame may be shifted by the operator while seated at the keyboard, there is provided an upright handle H^9 pivoted at H^{12} to a supporting bracket H^{13} at- 25 tached to the side of the keyboard frame near the front. The lower end of the handle is forked to receive a pin H^{10} projecting inwardly from the forward end of a link H^8 sliding in guideways of the supporting 30 bracket H^{13} and connected at its rear end to the longer arm of a horizontal bell crank lever H^7 whose shorter arm is formed to engage with a pin H^6 rising from an extended portion of one of the legs H^4 of the support- 35 ing frame H . Hence, by moving the handle H^9 forwardly and backwardly, the frame H may be shifted to the right and left, respectively, to bring one or the other series of slides E^7 , E^8 , into use as desired. A spring- 40 pressed detent H^{11} (Fig. 11) coöperating with recesses in the link H^8 serves to hold the parts yieldingly in their shifted position.

Referring now to the bails E^9 , they are inclosed within a boxlike structure J and are 45 mounted to rock about transverse rods J^4 , one for each group of bails and each common to all the bails of that group (Figs. 10 and 12). These pivot rods J^4 are fitted into the side walls J^2 of the boxlike structure, 50 while the arms of the bails project forwardly through slotted openings in its front wall J^1 so as to make engagement with the actuating slides E^7 , E^8 , as before described, the slotted openings being long enough to per- 55 mit a limited rocking of the bails such as is required in communicating the motions of the free slides E^8 to the active slides E^7 when the latter are connected. As thus arranged, the structure J with the contained bails and 60 pivot rods may be readily applied to or removed from the machine as a unit, the loose engagement between the bails and the actuating slides being made and broken as the unit is applied or removed. When in place, 65 the unit is fixed to the machine by means of

screws passing through extensions J^3 of the supporting structure.

To overcome any tendency of the parts to stick or bind, means are provided to lock the bails E^9 against movement when not in 70 use and to provide ample clearance between them and the actuating slides E^7 , E^8 , when the latter are shifted laterally by the movement of the supporting frame H . In the present instance, such means are in the form 75 of a plurality of transverse bars L (Fig. 14), one for each group of bails, and formed with cuts or notches l to coöperate with the pro- truding ends of the bails. To avoid un- necessary duplication only the third group 80 of bails is shown in its entirety, and conse- quently the full number of notches is shown only in connection with the associated bar. The bars L are connected together at one end by a cross plate L^2 secured to the box wall 85 J^1 by set screws L^3 passing through elong- ated slots in the cross plate, and at their opposite ends they are individually at- tached to the wall J^1 by further screws L^1 passing through similar elongated slots 90 formed in the bars directly. As a result of this construction, the bars may be shifted to the left and right, respectively, to locate the notches l out of registry with the bails 95 E^9 , as in Fig. 14, or in registry with such bails as in Fig. 15. The notches l are slightly beveled at one side, as at l^1 , so as to depress the bails as the bars begin their movement to the left and to permit the bails to assume their original position as the bars complete 100 their movement to the right. To effect the shifting of the bars automatically and at the proper time, they are connected to the op- erating handle H^9 which controls the shift- 105 ing of the frame H carrying the slides E^7 , E^8 . To make such connection, the cross plate L^2 has a lateral forked extension L^4 engaged with a pin rising from the longer arm of a horizontal bell crank lever L^5 whose shorter 110 arm is connected by a link L^6 to the longer arm of the bell crank lever H^7 before referred to (Fig. 12). Consequently, when the handle H^9 is operated to shift the slides E^7 , E^8 , to the right or left, the bars L will be shifted relatively in the opposite direction to lock 115 or release the bails E^9 according to the di- rection of movement. Thus, when the active slides E^7 are engaged with the finger keys E , the bars L occupy the position to the left with their notches l out of registry with the 120 protruding ends of the bails E^9 , which are then held depressed by the solid edges of the bars. When, however, the free slides E^8 are engaged with the finger keys, the bars L occupy the position to the right with their 125 notches in registry with the bails so as to permit them to be rocked upon the actua- tion of the keys. It is pointed out that due to the multiplying form of connections be- 130 tween the handle H^9 and the bars L , when

the slides E^7 , E^8 , are shifted to the right, the bars will be moved to the left more rapidly so as preliminarily to depress the bails E^9 and thereafter hold them depressed during 5 the remainder of the period of shifting. Of course when the parts are shifted in the opposite direction, the bails will be held depressed until the movement of the slides is almost completed. In this way, ample clearance 10 is provided between the bails and the slides during their relative movements, while at the same time the accidental rocking of the bails when the active slides E^7 are in use will be effectively prevented.

15 As a further safeguard when the free slides E^8 are in use, means are provided for locking against movement such of these slides as are connected with the finger keys not used in connection with the matrix 20 fonts Z . The means herein illustrated consists of a transverse bar K (Fig. 12) secured to the box wall J^1 and formed with a series of teeth K^1 arranged to engage in further notches e^8 in the rear edges of the slides E^8 .

25 The companion slides E^7 are formed with similar notches e^8 , but these latter are made wider so as to permit the slides to be moved freely when engaged with the finger keys. Thus, as shown in Figs. 16 to 18, when the 30 finger keys are engaged with the active slides E^7 , their widened notches e^8 , allow them to clear the teeth K^1 of the locking bar; whereas, when the free slides E^8 are engaged with the finger keys, the teeth K^1 enter the narrower notches e^8 of those slides and lock them against movement. The locking bar K is also indicated in the diagram of Fig. 19, wherein the finger keys having the shaded 35 key buttons are the only ones affected. In this way, in the use of the matrices X , all 40 of the finger keys of the keyboard may be actuated, while in the use of the matrices Z , some of the keys are locked against action and the remaining ones left free to be actuated. As before noted, these key locking 45 means are not essential to render the affected finger keys inactive, but act positively to prevent the accidental operation of the connected parts which might result from 50 the adherence of the companion slides E^7 , E^8 , or from other causes. Besides, an operator striking a locked key will know instantly that it is a wrong one and that no matrix has been released from the magazine. 55

In the foregoing description, the magazine A has been considered as of full length and in one piece, as customary, as a matter of fact, however, it is divided transversely 60 slightly below its median line into lower and upper sections 1^A and 2^A , respectively. These sections are supported on the base frame A^1 with the complementary portions of the grooves a in proper registry, the upper ends of the ribs a^1 of the lower section

being beveled or chamfered, as indicated in Fig. 5, to compensate for any slight irregularity in this respect. Ordinarily, and in most cases, the entire font of matrices is stored in the lower section 1^A only, the number of matrices in the font being reduced so that all of the matrix columns will stop short of the upper section 2^A . As herein constructed, the parts permit the use of ten individual matrices in each matrix column, 75 which number in practice has been found to be entirely satisfactory for the larger sizes employed. In such an arrangement, therefore, the lower section 1^A constitutes the magazine proper, and the upper section 2^A 80 merely a conductor to carry and guide the matrices thereto from the magazine-entrance. Hence, in interchanging fonts, it is necessary only to remove the lower section 1^A , leaving the upper section 2^A in place 85 on the base frame to coöperate with the substitute magazine sections. This construction is very advantageous for reasons fully explained in the companion application repeatedly referred to. 90

In order that the former may be removed independently, the magazine sections 1^A and 2^A are attached to the base frame A^1 by separate means. The section 1^A is provided on its upper side with the customary transverse reinforcing ribs a^2 , resting upon the base frame, and the foremost one of which is engaged with the upstanding shoulders A^8 thereon (Fig. 2), this engagement of the parts insuring the retention of the magazine section in proper position on the frame, while permitting it to be lifted therefrom when desired. The rearmost one of the rails a^2 (Fig. 5) is extended beyond the edges of the magazine so that it may be supported 100 in a suitable rack. The upper magazine section or conductor 2^A is similarly formed with transverse ribs a^3 , resting upon the base frame A^1 but in this instance, the foremost one of the rails is slightly thicker than the others and is seated in a corresponding recess formed in the upper face of the base frame, whereby the section is securely though detachably held in position thereon. Before removing the magazine section 1^A , 115 it is customary to swing the latter upwardly in the manner before described to disengage it from the underlying bank of escapements and locate it above the front plate B , as shown by the dotted lines in Fig. 2, when 120 it may be drawn forwardly from the front of the machine.

It may happen that matrices will become lodged between the two magazine sections at the time of removal of the lower one. 125 Hence the top plate of the upper section 2^A is provided at its lower end with a hinged plate a^4 (Figs. 2 and 5), which will yield in such event and thus avoid injury to the parts. 130

In the use of fonts comprising thinner matrices, it may be desired to employ a larger quantity of matrices in the machine. In this event, the matrices may be stored in both magazine sections 1^A and 2^A, the latter allowing the matrix columns to extend all the way back to the magazine-entrance. However, to secure same result, it is preferred to remove the two magazine sections and substitute an integral magazine of full length, this being far more practical. 70

As previously stated, I have shown my invention only in preferred form and by way of example and as applied to the particular kind of machine described, but obviously many modifications and alterations therein and in its mode of adaptation will suggest themselves to those skilled in the art and still be comprised within its scope. It 80 should also be noted that while the various features described are very closely related and mutually coöperate to bring about the desired results, many of them might be used alone or in connection with other features 85 to good advantage.

Having thus described my invention, its construction and mode of operation, what I claim and desire to secure by Letters Patent of the United States is as follows:

30 1. In a typographical machine, the combination of a distributor having a series of combinations and a channeled member to receive the matrices therefrom and having its channels arranged in varying relations 90 to the corresponding distributor-combinations, for the purpose described.

2. In a typographical machine, the combination of a distributor having a series of combinations, a channeled magazine, and an 100 intermediate magazine entrance having partitions dividing it into channels, the partitions constituting the left or rear walls of said channels being located in vertical planes offset different distances from the 105 corresponding distributor-combinations, for the purpose described.

3. In a typographical machine equipped with matrices having tooth-combinations located in different setwise positions thereon, the combination of a distributor having a series of combinations to coöperate with those of the matrices, and a channeled member to receive the matrices from the distributor and having its channels arranged 110 in varying relations to the corresponding distributor-combinations in accordance with the different setwise positions of the coöperating tooth-combinations on the respective matrices.

60 4. In a typographical machine equipped with matrices having tooth-combinations located in different setwise positions thereon, the combination of a distributor having a series of combinations to coöperate with those of the matrices, a channeled magazine

to contain the matrices, and an intermediate magazine entrance having partitions dividing it into channels, the partitions constituting the left or rear side walls of said channels being located in vertical planes 70 offset different distances from the corresponding distributor-combinations in accordance with the different setwise positions of the coöperating tooth-combinations on the respective matrices. 75

5. In a typographical machine adapted to be equipped with a magazine containing a set of matrices having tooth-combinations arranged thereon in the same setwise position throughout the set, or with a magazine containing a set of matrices having tooth-combinations arranged thereon in different setwise positions throughout the set, the combination of a distributor having combinations to coöperate with those of the 85 matrices, and two channeled magazine entrances movably arranged so that one or the other may be brought into operative relation to the selected magazine and distributor, one of said entrances having its channels arranged in the same or unvarying relations to the corresponding distributor-combinations to accommodate matrices of one set, and the other entrance having its channels arranged in varying relations to 95 the corresponding distributor-combinations to accommodate matrices of the other set.

6. In a typographical machine, the combination of a distributor having a series of combinations, and a member to receive the 100 matrices therefrom and having a materially less number of matrix channels, the said channels being spaced apart along the entire portion of the distributor occupied by said combinations and arranged in varying 105 operative relations to a like number of distributor combinations.

7. In a typographical machine, the combination of a distributor having a series of combinations, a magazine entrance provided 110 with partitions dividing it into a materially less number of matrix channels, the said channels being spaced apart along the entire portion of the distributor occupied by said combinations and arranged in varying 115 operative relations to as many different distributor combinations, and a magazine having matrix channels communicating with those of the magazine entrance.

8. In a typographical machine, the combination of a magazine containing matrices formed with tooth-combinations, a distributor having a series of combinations to coöperate with those of the matrices and spaced apart in one manner, and an intermediate magazine entrance having partitions dividing it into channels spaced apart in a different manner, the said matrices having their tooth-combinations located in different setwise positions, in accordance with 125 130

the varying relations between the entrance channels and the corresponding distributor-combinations.

9. In a typographical machine, the combination of a magazine formed with a series of grooved channels, and a set of matrices stored in columns in said magazine and formed with projecting ears engaged in certain of said grooved channels, the others of which are left vacant, said projecting ears being located in different setwise positions on the respective matrices to allow them to overlap the vacant grooved channels in taking up the additional space provided by said vacant channels.

10. In a typographical machine equipped with matrices formed with projecting ears located in different setwise positions thereon, the combination of a magazine formed with grooved channels wherein the projecting ears of the matrices engage, a distributor, and an intermediate magazine entrance having partitions dividing it into matrix channels, the said channels being arranged in varying relations to the appropriate grooved channels of the magazine in accordance with the different setwise positions of the projecting ears on the respective matrices.

11. In a typographical machine adapted to be equipped with a set of matrices formed with projecting ears located in the same setwise position thereon throughout the set, or with a set of matrices formed with projecting ears located in different setwise positions thereon throughout the set, the combination of a magazine containing a selected one of the matrix sets and formed with grooved channels wherein the projecting ears engage, two channeled magazine entrances movably arranged so that one or the other may be brought into operative relation to the magazine, one of said entrances having its channels arranged in the same or unvarying relations to the appropriate channels of the magazine to accommodate matrices of one set, and the other entrance having its channels arranged in varying relations to the appropriate channels of the magazine to accommodate matrices of the other set, and means for distributing the matrices of the selected set into the proper channels of the operative magazine entrance.

12. In a typographical machine, the combination of a magazine provided with a series of grooved channels, a set of matrices stored in columns in said magazine and formed with projecting ears engaged in certain of said grooved channels, said projecting ears being located in different setwise positions on the respective matrices to allow them to overlap the remaining grooved channels, a distributor, and an intermediate magazine entrance having only as many channels as there are matrix columns in the magazine, said channels being arranged in

varying relations to the appropriate grooved channels of the magazine in accordance with the different setwise positions of the projecting ears on the respective matrices.

13. In a typographical machine adapted to be equipped with a set of matrices formed with projecting ears located in the same setwise position thereon throughout the set, or with a set of matrices formed with projecting ears located in different setwise positions thereon throughout the set, the latter set having fewer characters than the former, the combination of a magazine containing a selected one of the matrix sets and formed with grooved channels wherein the projecting ears engage, the magazine entrances movably arranged so that one or the other may be brought into operative relation to the magazine, one of said entrances having a like number of matrix channels occupying the same relation to the respective magazine channels to accommodate matrices of one set, and the other entrance having a materially less number of matrix channels occupying varying relations to the appropriate grooved channels of the magazine to accommodate matrices of the other set, and means for distributing the matrices of the selected set into the proper channels of the operative magazine entrance.

14. A magazine entrance for typographical machines having partitions dividing it into channels, at least one of said channels being provided with guiding surfaces projecting thereinto from both sides to engage the projecting ears of the matrices and guide them therefrom independently of the partitions.

15. In a typographical machine comprising matrices formed with projecting ears, the combination of a magazine formed with grooved channels, a distributor, and an intermediate entrance having partitions dividing it into matrix channels arranged in varying relations to the grooved channels of the magazine and provided with guiding surfaces to engage the projecting ears of the matrices as they pass therethrough and direct them into the appropriate grooved channels of the magazine.

16. In a typographical machine equipped with matrices formed with projecting ears located in different setwise positions thereon, the combination of a magazine to contain such matrices and formed with grooved channels wherein their projecting ears engage, a distributor formed with a series of combinations, and an intermediate magazine entrance having partitions dividing it into matrix channels leading from certain of the distributor-combinations to the appropriate grooved channels of the magazine, and the said matrices being further formed with tooth-combinations located in different setwise positions thereon so as to be dropped

- into the proper channels of the magazine entrance when released from the distributor.
17. In a typographical machine, the combination of two magazine entrances permanently located in the machine and differing as to form and movably mounted so that either may be set in operative position, and distributing mechanism for delivering the matrices to the magazine entrance in operative position.
18. In a typographical machine, the combination of a stationary distributor, and two magazine entrances permanently mounted in the machine and movably arranged so that either may be brought into operative relation to said distributor.
19. In a typographical machine, the combination of a stationary distributor, and two magazine entrances of different form permanently mounted in the machine and movably arranged so that either may be brought into operative relation to said distributor.
20. In a typographical machine, the combination of a stationary distributor, and two independently mounted magazine entrances permanently located in the machine and movably arranged so that either may be brought into operative relation to said distributor.
21. In a typographical machine, the combination of a distributor, two magazine entrances permanently mounted in the machine and movably arranged so that either may be brought into the operative relation to the distributor, one of said entrances being pivoted to a suitable part of the machine, and a movable supporting frame for the other entrance arranged to carry it bodily into and out of operative position.
22. In a typographical machine, the combination of a distributor, a base frame whereon the magazine is removably mounted, a magazine entrance pivoted to said base frame so as to be movable into and out of operative relation to the distributor, a substitute magazine entrance, and a separate supporting frame for the latter entrance movable to carry it into and out of operative relation to said distributor.
23. In a typographical machine, the combination of a distributor, a base frame whereon the magazine is removably mounted, a magazine entrance pivoted to said frame so as to be movable into and out of operative relation to the distributor, a substitute magazine entrance, a separate supporting frame for the latter entrance movable to carry it into and out of operative relation to said distributor, and means for locking the supporting frame to the magazine base frame when the substitute entrance is in use.
24. In a typographical machine, the combination of a magazine base frame pivoted near its upper end so as to swing upwardly to permit the removal of a magazine, a magazine entrance arranged to coöperate with the magazine on said frame, and a swinging supporting frame hinged to the fixed machine frame carrying said entrance and having its free end engaged with the magazine base frame, said supporting frame being arranged to yield when the base frame is rocked without breaking its engagement therewith.
25. In a typographical machine, the combination of a magazine base frame pivoted near its upper end so as to swing upwardly to permit the removal of a magazine, a magazine entrance arranged to coöperate with the magazine on said frame, and a swinging supporting frame carrying said entrance and having its free end engaged with the magazine base frame, the said supporting frame being formed in relatively movable sections adapted to yield when the base frame is rocked without breaking the engagement between said frames.
26. In a typographical machine, the combination of a distributor, a magazine entrance movable into and out of operative relation to said distributor, a swinging supporting frame whereon the entrance is mounted and formed in two pivoted sections, and a spring connected at its opposite ends to the two sections and holding them yieldingly in normal relation.
27. In a typographical machine, the combination of a swinging frame formed in two pivoted sections, a magazine entrance pivoted to the lower section of said frame and having a stop to limit its pivotal movement in one direction, and a spring connected at one end to the entrance and at its other end to the upper section of the frame and tending constantly to hold the several parts in normal relation.
28. In a typographical machine adapted to be equipped with interchangeable magazines, one containing a set of matrices arranged in one order as to character and the other containing a set of matrices arranged in a different order as to character, the combination of a keyboard, and means whereby the finger keys of said keyboard may be operatively connected to the appropriate channels of either selected magazine so as to effect the release of the corresponding matrices of the contained set.
29. In a typographical machine adapted to be equipped with interchangeable magazines, one containing a set of matrices arranged in one order as to character and the other containing a set of matrices having a materially less number of characters and arranged in a different order as to character, the combination of a keyboard having as many finger keys as there are characters in the first set of matrices and arranged in the same order as to character, and means

whereby said keyboard may be operatively connected to the appropriate channels of either selected magazine so as to effect the release of the corresponding matrices of the 5 contained set.

30. In a typographical machine adapted to be equipped with interchangeable channeled magazines, one containing a set of matrices occupying certain channels according to character and the other containing a set of matrices having a materially less number of characters and occupying differently located channels according to character, the combination of a keyboard having as many

10 finger keys as there are characters in the first set of matrices, and means whereby said finger keys may be operatively connected to the appropriate channels of either selected magazine so as to effect the release of the 15 corresponding matrices of the contained set.

31. In a typographical machine adapted to be equipped with interchangeable magazines, one containing a set of matrices occupying certain channels according to character and the other containing a set of matrices

20 occupying differently located channels according to character, the combination of a keyboard, different series of connections through which the finger keys of said keyboard control the release of like matrices of the two sets, and means for rendering one or the other series of connections active according to the matrix set contained in the 25 selected magazine.

32. In a typographical machine, the combination of a magazine adapted to contain a set of matrices arranged in one order as to character and a set of matrices arranged in a different order as to character, a bank

30 of escapements to control the release of the matrices from the magazine, a keyboard, and means for operatively connecting the finger keys to the escapements in one location or another according to the matrix set contained in the 35 magazine.

33. In a typographical machine, the combination of a series of escapement actuating devices, a series of finger keys, and adjustable means operative under one adjustment 40 to connect certain of said keys to the respective actuating devices of a given group and operative under another adjustment to connect other of said keys to the respective actuating devices of the same group.

34. In a typographical machine, the combination of an escapement actuating device, two finger keys, and means whereby either of said keys may be connected to said actuating device to the exclusion of the other, as 45 desired.

35. In a typographical machine, the combination of a series of escapement actuating devices, a series of finger keys, and adjustable means operative under one adjustment 50 to connect the various finger keys to the re-

spective actuating devices of the series and operative under another adjustment to connect certain of said keys to different selected ones of said actuating devices.

36. In a typographical machine, the combination of a series of actuating devices, a series of finger keys, and adjustable means operative under one adjustment to connect certain selected finger keys to the respective actuating devices of a given group and operative under another adjustment to connect said selected keys to different actuating devices and other of the keys to the respective actuating devices of the given group. 70

37. In a typographical machine, the combination of a series of actuating escapement devices, a series of finger keys, and adjustable means operative under one adjustment to connect the various finger keys to the respective actuating devices of the series in a given order and operative under another adjustment to connect certain of said keys to as many different actuating devices in a different order. 80

38. In a typographical machine, the combination of a magazine adapted to contain a set of matrices arranged in one order as to character and a set of matrices having fewer characters and arranged in a different order as to character, a single keyboard 95 having as many finger keys as there are characters in the first set of matrices, intermediate adjustable means for operatively connecting said finger keys to the magazine channels in one location or another according to the matrix set contained in the magazine, and means for preventing the operation of the unused finger keys when the magazine contains the second matrix set. 100

39. In a typographical machine adapted to be equipped with a magazine containing a set of matrices occupying certain channels according to character and with a magazine containing a set of matrices having fewer characters and occupying differently located channels according to character, the combination of a keyboard having as many finger keys as there are characters in the first set of matrices, means whereby said finger keys may be operatively connected to the appropriate channels of the selected magazine so as to effect the release of the corresponding matrices of the contained set, and means for preventing the operation of the surplus finger keys when the selected magazine contains matrices of the second set. 110

40. In a typographical machine, the combination of a magazine adapted to contain a set of matrices arranged in one order as to character and a set of matrices arranged in a different order as to character, a bank of escapements to control the release of the matrices from the magazine, actuating devices connected to the escapements, a single keyboard controlling the operation of said 125

130

actuating devices, and intermediate adjustable means for permitting the operation of all of the escapements or preventing the operation of certain of them according to the 5 matrix set contained in the magazine.

41. In a typographical machine, the combination of a magazine adapted to contain a set of matrices arranged in one order as to character and a set of matrices having fewer 10 characters and arranged in a different order as to character, a bank of escapements to control the release of the matrices from the magazine, devices for actuating said escapements and divided into groups, one group 15 alone adapted to be used in the release of matrices of one set, and all of said groups adapted to be used conjointly in the release of matrices of the other set, a single keyboard controlling the operation of said actuating devices, and intermediate adjustable 20 means for permitting or preventing the joint operation of said groups according to the matrix set contained in the magazine.

42. In a typographical machine the combination of a magazine adapted to contain a set of matrices occupying certain channels according to character and a set of matrices occupying differently located channels according to character, escapements to control 25 the release of the matrices from the magazine, finger keys, connections leading therefrom to the escapements, and means for adjusting said connections so as to cause the finger keys to actuate the escapements 30 in one location or another according to the matrix set contained in the magazine.

43. In a typographical machine, the combination of a magazine provided with a series of escapements, a keyboard, an intermediate 35 means for operatively connecting said keyboard in whole or in part to the escapements, as desired.

44. In a typographical machine, the combination of a series of escapement actuating 40 devices, a keyboard, and intermediate means for operatively connecting said keyboard in whole or in part to the actuating devices, as desired.

45. In a typographical machine, the combination of a series of escapement-actuating 45 devices, a keyboard, and adjustable means whereby the finger keys of said keyboard may be operatively connected to differently located escapement-actuating devices in 50 such manner that those particular devices operated by the corresponding finger keys under one adjustment of said means will be operated by different selected ones of the finger keys under another adjustment of 55 said means.

46. In a typographical machine, the combination of a series of escapement-actuating 60 devices, a keyboard, different series of connections through which the finger keys of 65 said keyboard operate differently located

escapement-actuating devices in such manner that those particular devices operated by the corresponding finger keys through one series of connections will be operated by different selected ones of the finger keys 70 through the other series of connections, and means for rendering either series of connections active, as required.

47. In a typographical machine, the combination of a series of power-operated escapement-actuating devices, a keyboard controlling the operation of said devices, and intermediate adjustable means through which the finger keys of said keyboard effect 75 the operation of the escapement-actuating devices in one location or another according to the adjustment of said means, said means being arranged in such manner that those particular actuating devices operated by the corresponding finger keys under one adjustment thereof will be operated by different selected ones of the finger keys under 80 another adjustment thereof.

48. In a typographical machine, the combination of a series of power-operated escapement-actuating devices, a keyboard, direct connections through which the finger keys of said keyboard operate certain selected actuating devices, indirect connections through 85 which they operate differently located actuating devices of those operated by the finger keys through the direct connections, and means for causing said keys to act through the direct or indirect connections, as required.

49. In a keyboard mechanism for typographical machines, the combination with a cam yoke and a trip dog therefor, of a finger key, an intermediate slide directly connecting the key and trip dog, and means for making and breaking such connection at 100 will.

50. In a keyboard mechanism for typographical machines, the combination with a cam yoke and a trip dog therefor, of a finger key, and an intermediate slide connected 105 constantly with the trip dog and shiftable laterally into and out of engagement with the finger key.

51. In a keyboard mechanism for typographical machines, the combination with 110 two cam yokes and trip dogs therefor, of two corresponding finger keys, a pair of slides arranged between each key and the respective trip dog, one of said slides being free from and the other actively connected 115 to said dog, means for shifting said slides to effect the alternate engagement of the free and active slides with their corresponding finger keys, and means for locking the free slides against movement when engaged with 120 said finger keys.

52. In a keyboard mechanism for typographical machines, the combination with two cam yokes and trip dogs therefor, of two corresponding finger keys, a pair of slides 125

- arranged between each key and the respective trip dog, one of such slides being free from and the other actively connected to said dog, means for shifting said slides to effect the alternate engagement of the free and active slides with their corresponding finger keys, and a connecting member arranged to be operatively engaged with the free slide of one key and the active slide of the other key in one position of the slides and disengaged from said parts in the other position of the slides.
53. In a keyboard mechanism for typographical machines, the combination with a series of cam yokes and trip dogs therefor, of a series of finger keys, a pair of slides arranged between each key and the respective trip dog, one of said slides being free from and the other actively connected to said dog, means for effecting the alternate engagement of the free and active slides with their corresponding finger keys, and connections actuated by the free slides when engaged with the finger keys for operating the active slides associated with other keys, for the purpose described.
54. In a keyboard mechanism for typographical machines, the combination with a series of cam yokes and trip dogs therefor, of a series of finger keys, a pair of slides arranged between each key and the respective trip dog, one of said slides being free from and the other actively connected to said dog, a supporting frame for said slides shiftable in opposite directions to effect the alternate engagement of the free and active slides with their corresponding finger keys, and connecting members idle when the active slides are connected to the finger keys, and arranged to transmit the motion of the free slides when engaged with said keys to the active slides of other keys, for the purpose described.
55. In a keyboard mechanism for typographical machines, the combination with a series of cam yokes and trip dogs therefor, of a series of finger keys, a pair of slides arranged between each key and the respective trip dog, one of said slides being free from and the other actively connected to said dog, a supporting frame for said slides shiftable in opposite directions to effect the alternate engagement of the free and active slides with their corresponding finger keys, and U-shaped rocking bails, idle when the active slides are engaged with the finger keys, and arranged when free slides are engaged with said keys to connect such slides with the active slides of other keys.
56. A structure as specified in 55, in combination with means for depressing the forward ends of the connecting bails therein recited as the slides are shifted so as to provide ample clearance between said parts.
57. A structure as specified in 55, in combination with means for locking the connecting bails against rocking when the active slides are engaged with the finger keys.
58. In a keyboard mechanism for typographical machines, the combination with a series of cam yokes and trip dogs therefor, of a series of finger keys, a pair of slides arranged between each key and the respective trip dog, one of such slides being free from and the other actively connected to said trip dog, means for effecting the alternate engagement of the free and active slides with their corresponding finger keys, connections actuated by certain of the free slides when engaged with the finger keys for operating the active slides of other keys, and means for locking other free slides against movement when so engaged.
59. In a keyboard mechanism for typographical machines, the combination with a series of finger keys, a pair of slides arranged between each key and the respective trip dog, one free from and the other actively connected to said dog and each formed with notches in its opposite edges, means for shifting the slides laterally to effect the engagement of the finger keys in the forward notches of the free or active slides as desired, and connecting bails arranged in one position of the parts with their opposite ends in position to engage in the rear notches of both the free and active slides and in the other position of the parts to engage only in the rear notches of the active slides, the latter rear notches of the active slides being widened to permit lost motion between them and the bails, for the purpose described.
60. In a keyboard mechanism for typographical machines, the combination of a series of power-driven cam yokes, a series of finger keys, one for each cam yoke, devices to establish direct or indirect connections between the finger keys and the cam yokes, and means for adjusting said devices to make the direct or indirect connections as required.
61. In a keyboard mechanism for typographical machines, the combination of a series of finger keys and means for locking certain of said keys out of action while permitting the remaining keys to be actuated.
62. In a keyboard mechanism for typographical machines, the combination of a series of finger keys, and means for locking certain of said keys out of action while permitting the remaining keys to be actuated, the said means adapted to be rendered inactive at will to permit the operation of all of said keys.
63. In a keyboard mechanism for typographical machines, the combination of two series of key-controlled actuating slides, a series of bails to connect the slides of one

series with selected slides of the other series, means for adjusting said parts relatively in opposite directions to make or break such connection as desired, and means 5 for preventing the movement of the bails when not in use.

64. In a keyboard mechanism for typographical machines, the combination of two series of key-controlled actuating slides, a 10 series of bails to connect the slides of one series with selected slides of the other series, means for adjusting said parts relatively in opposite directions to make or break such connection as desired, and automatic means 15 for locking the bails against movement except when in use.

65. In a keyboard mechanism for typographical machines, the combination of two series of key-controlled actuating slides, a 20 series of bails to connect the slides of one series with selected slides of the other series, means for adjusting said parts relatively in opposite directions to make or break such connection as desired, and means controlled 25 by said adjusting means for locking the bails against movement.

66. In a keyboard mechanism for typographical machines, the combination of two series of key-controlled actuating slides, a 30 series of bails to connect the slides of one series with selected slides of the other series, a supporting frame wherein the slides are mounted and adjustable to different operative positions to make or break such connection as desired, and automatic means for 35 locking the bails against movement except when the supporting frame occupies one only of its operative positions.

67. In a keyboard mechanism for typographical machines, the combination of two 40 series of key-controlled actuating slides, a series of connecting bails having their forward ends arranged in engaging relation to the slides, a supporting frame wherein the 45 slides are mounted and adjustable in opposite directions to vary their engaging relation to the connecting bails, and movable locking bars coöperating with the forward ends of the connecting bails to prevent their 50 movement at an improper time.

68. In a keyboard mechanism for typographical machines, the combination of two 55 series of key-controlled actuating slides, a series of connecting bails having their forward ends arranged in engaging relation to said slides, means for adjusting said parts relatively in opposite directions to alter their engaging relation, and automatic means for holding the forward ends of the bails de- 60 pressed during the relative adjustment of the parts.

69. In a keyboard mechanism for typographical machines, the combination of two 65 series of key-controlled actuating slides, a series of connecting bails having their for-

ward ends arranged in engaging relation to said slides, means for adjusting said parts relatively in opposite directions to alter their engaging relation, and automatic means for holding the forward ends of the bails de- 70 pressed during the relative adjustment of the parts, said means being actuated to release the bails when the parts are adjusted in one direction only.

70. In a keyboard mechanism for typographical machines, the combination of two series of key-controlled actuating slides, a series of connecting bails having their forward ends arranged in engaging relation to said slides, means for adjusting said parts 75 relatively in opposite directions to alter their engaging relation, and automatic means acting to depress and hold depressed the forward ends of the bails before and after the relative adjustment of the parts in 80 one direction, respectively.

71. In a keyboard mechanism for typographical machines, the combination of two series of key-controlled actuating slides, a series of connecting bails having their for- 90 wards ends arranged in engaging relation to said slides, means for adjusting said parts relatively in opposite directions to alter their engaging relation, and automatic means acting to maintain the forward ends 95 of the connecting bails depressed during the relative adjustment of the parts, said means being actuated when the parts are adjusted in one direction to release the bails upon the completion of such adjustment. 100

72. In a keyboard mechanism for typographical machines, the combination of two series of key-controlled actuating slides, a series of connecting bails having their forward ends arranged in engaging relation to 105 said slides, means for adjusting said parts relatively in opposite directions to alter their engaging relation, and automatic means for locking the bails against movement during the relative adjustment of said parts, 110 said means being rendered active before such adjustment when the parts are adjusted in one direction.

73. In a keyboard mechanism for typographical machines, the combination of two 115 series of key-controlled actuating slides, a series of connecting bails having their forward ends arranged in engaging relation to said slides, means for adjusting said parts relatively in opposite directions to alter their 120 engaging relation, and automatic means for locking the bails against movement during the relative adjustment of said parts, said means being rendered inactive after such adjustment when the parts are adjusted in 125 one direction.

74. In a keyboard mechanism for typographical machines, the combination of two series of key-controlled actuating slides, a series of connecting bails having their for- 130

ward ends arranged in engaging relation to the slides, a supporting frame wherein the slides are mounted and adjustable in opposite directions to vary their engaging relation to the connecting bails, movable locking bars coöoperating with the forward ends of the connecting bails, and connections between the supporting frame and the locking bars whereby the latter are moved to active or inactive position before or after the adjustment of the supporting frame according to its direction of movement.

75. In a keyboard mechanism for typographical machines, the combination of two series of key-controlled actuating slides, a series of connecting bails having their forward ends arranged in engaging relation to the slides, a supporting frame wherein the slides are mounted and adjustable to vary their engaging relation to the connecting bails, movable locking bars coöoperating with the forward ends of the connecting bails, a hand lever movable in opposite directions, and connections from the hand lever to both said supporting frame and locking bars, the said connections being such that the movement of the hand lever in one direction effects first the shifting of the locking bars to active position and then the adjustment of the supporting frame, while its movement in the opposite direction effects first the adjustment of the supporting frame and then the shifting of the locking bars to inactive position.

35 76. A keyboard mechanism as specified in claim 74 characterized by the fact that the locking bars therein recited act when in active position to hold the forward ends of the connecting bails depressed to clear the actuating slides during the relative adjustment of the parts.

45 77. In a typographical machine, the combination of a magazine containing a set of matrices occupying certain channels according to character and replaceable in operative position by another magazine containing a set of matrices occupying differently located channels according to character, a keyboard having its finger keys operatively connected 50 to the appropriate channels of the first-mentioned magazine, and intermediate adjustable means whereby said finger keys may be operatively connected to the appropriate channels of the second-mentioned magazine 55 when the latter is in use so as to effect the release of the corresponding matrices in the contained set notwithstanding their different location in the magazine channels.

60 78. In a typographical machine, the combination of a magazine containing a set of matrices occupying certain channels according to character and replaceable in operative position by another magazine containing a set of matrices occupying differently located

channels according to character, a keyboard, 65 matrix releasing connections leading from the finger keys of said keyboard to the appropriate channels of the first-mentioned magazine, and means for adjusting said connections when the second-mentioned magazine is brought into use so as to cause the finger keys to effect the release of the corresponding matrices in the contained set notwithstanding their different location in the magazine channels.

75 79. In a typographical machine, the combination of a magazine containing a set of matrices occupying certain channels according to character and replaceable in operative position by another magazine containing a 80 set of matrices having fewer characters and occupying differently located channels according to character, a keyboard connected as a whole to the appropriate channels of the first-mentioned magazine, and means whereby said keyboard may be connected in part only to the appropriate channels of the second-mentioned magazine when the latter is substituted for the other.

80 81. In a typographical machine adapted to 90 be equipped with interchangeable magazines, one containing a set of matrices occupying certain channels according to character and the other containing a set of matrices occupying differently located channels according 95 to character, the combination of a keyboard, means whereby the finger keys of said keyboard may be operatively connected to the appropriate channels of either selected magazine so as to effect the release of the 100 corresponding matrices of the contained set, and distributing mechanism for returning the matrices to their proper channels in the selected magazine irrespective of their location therein.

105 81. In a typographical machine adapted to be equipped with interchangeable magazines, one containing a set of matrices occupying certain channels according to character and the other containing a set of matrices 110 occupying differently located channels according to character, the combination of a keyboard, means whereby the finger keys of said keyboard may be operatively connected to the appropriate channels of either selected magazine so as to effect the release of the corresponding matrices of the contained set, a distributor to coöperate with said selected magazine, and two magazine entrances movably arranged so that one or the other may 120 be brought into operative relation to the magazine and distributor according to the matrix set contained in the selected magazine.

125 In testimony whereof I have affixed my signature hereto.

DAVID S. KENNEDY.
